UNITED STATES PATENT OFFICE.

JAMES A. MEHRHEN AND JOHN H. HOWARD, OF EXETER, CALIFORNIA.

SWITCH-OPERATING MECHANISM FOR ELECTRIC MOTORS.

SPECIFICATION forming part of Letters Patent No. 770,378, dated September 20, 1904.

Application filed October 6, 1903. Serial No. 175,996. (No model.)

To all whom it may concern:

Be it known that we, JAMES A. MEHRHEN and JOHN H. HOWARD, citizens of the United States, residing at Exeter, in the county of 5 Tulare and State of California, have invented a new and useful Switch-Operating Mechanism for Electric Motors, of which the following is a specification.

This invention relates to certain improvements in switch-operating mechanism, and has for its principal object to provide a means for automatically cutting off the current of an electric motor in the event of accidental stoppage of the mechanism to which the motor is 10 connected.

The invention, while applicable to machines of various character, is adapted more especially for use in connection with pumping plants wherein the operation of the pump 15 will at times cease from lack of water or loss of priming.

A further object of the invention is to provide a switch-operating mechanism in the form of a governor-controlled mechanism that 20 is set into operation by a portion or all of the water raised or moved by a pump.

With these and other objects in view, as will 25 more fully hereinafter appear, the invention consists in the novel construction and arrangement of parts hereinafter described, illustrated in the accompanying drawings, and particularly pointed out in the appended claims, it being understood that various changes in the form, proportions, size, and 30 minor details of the structure may be made without departing from the spirit or sacrificing any of the advantages of the invention.

In the accompanying drawings, Figure 1 is 35 an elevation of a switch-operating mechanism constructed in accordance with the invention and illustrating the same as employed in connection with a pump. Fig. 2 is a similar view of a portion of the same, the governor-shaft and its supports being shown in section 40 in order to more clearly illustrate the construction.

Similar numerals of reference are employed 45 to indicate corresponding parts throughout both figures of the drawings.

In the drawings, 1 represents a pump that 50 may be of any ordinary type, the pump being operatively connected to an electric motor 2, to which current is conducted by wires 3. In the circuit is arranged a switch 4, that is moved to open position in order to cut off the 55 current when the pumping operation ceases.

10 indicates a suitable frame having upper and lower ball-bearings 11 and 12 for the reception of a vertically-disposed shaft or spindle 13. The shaft 13 is provided with a pulley 14, connected by a suitable belt 15 to a pulley 16, arranged on the same shaft with a small water-wheel 17, that is operated by the water issuing from the pump, and this water-wheel may be of any ordinary type and ar- 60 ranged in any suitable manner without departing from the invention, it being understood that the water-wheel is suggestive of a movable element which may be in the form of any operative mechanism. 65

The shaft 13 is hollow, and extending therethrough is a rod or stem 18, the lower end of which is provided with a grooved collar 19 for the reception of a transversely-disposed bar 20, that extends through vertical slots 70 formed at diametrically opposite points in the hollow shaft 13, so that the shaft and arm may be rotated without effecting corresponding rotative movement of the rod 18.

To the opposite sides of the shaft 13 are secured horizontal arms 21, to which are pivoted the upper ends of ball-carrying arms 22, which may be of the type ordinarily employed in centrifugal governors, and said arms are connected by links 23 to the opposite ends of 80 the bar 20, so that when rotative movement is imparted to the governor-shaft the ball-carrying arms will raise and maintain the rod 18 in elevated position, and when the operation of the shaft ceases the rod 18 will fall. 85

To the upper member of the supporting-frame 10 is secured a transversely-disposed bar 25, having a guiding-opening for the upper portion of the rod 18, and the upper end of said rod is connected to one end of a trigger 90 95 27 in the form of a lever that is pivoted at an intermediate point to a bracket or standard 28, carried by the frame, the opposite end

of said lever being provided with an opening 29 for the reception of a pin 30, carried by a pivoted bar 31. The bar 31 has a hinged or pivoted connection with the face portion of the frame, and to its outer face is secured a bracket 32, on which is hung a weight 33, that normally tends to move the bar 31 to the position shown in dotted lines in Fig. 1, this movement being prevented by the engagement of the pin 30 in the opening 29 so long as the shaft 13 is revolving. In order to limit the movement of the bar 31, it is connected by a flexible chain or cord 34 to the main frame, this serving as a checking means for stopping the outward movement of the bar when the latter has assumed the position shown in dotted lines.

The switch is of the ordinary type and is provided with a handle 37, that is connected by a cord or chain 38 to the weight 33, the cord or chain extending from one or more guiding-shafts 39 in accordance with the position of the motor and its distance from the governing mechanism.

In the operation of the device the current of water issuing from the pump operates the water wheel or turbine, and through the belt connection the shaft 13 is rotated so long as the pumping operation continues. The governor-arms are maintained in elevated position by centrifugal force, and the rod 18 is moved upward, so that the outer end of the trigger-lever will be held down to the position shown in full lines in Fig. 1 and the bar 31 maintained in vertical position. When the pumping operation ceases, the shaft 13 will stop and the governor-arms will fall, resulting in upward movement of the outer end of the trigger-lever 27 and the release of the pin 30. The weight 33 will thereupon cause the bar 31 to move to the dotted-line position, the outward movement of said bar being suddenly checked by the chain or cord 34 and the weight under the impetus of its previous movement sliding from the bracket 32 and exerting sufficient downward strain on the cord or chain to move the switch and cut off the supply of current to the motor, so there will be no waste of current should the pump cease its effective operation from lack of water or loss of priming.

Having thus described the invention, what is claimed is—

1. In combination, a motor, an energized circuit including a switch, a governor for controlling the switch, a pump having operative connection with the motor, and means operable by the pump-actuated fluid for driving the governor at a speed dependent on the quantity and pressure of said fluid.

2. In combination, a motor, an energized circuit including a switch, a pump having operative connection with the motor, a governor, a switch-operating mechanism controlled by the governor, and a means operable continuously by the fluid issuing from the pump during all the time said pump is in operation and connected to said governor.

3. In combination, a motor, an energized circuit including a switch, a revolute governor having operative connection with the switch, a pump operatively connected to the motor, a revolute member operable by the current of fluid actuated by the pump, and a means for connecting said revolute member to said governor.

4. A switch-operating mechanism comprising a governor, means for operating the same, a weight-carrying member normally locked by the governor, and a weight carried by said member and connected to the switch, said weight being released when the operation of the governor ceases.

5. In combination, a pivotally-mounted bar having a weight-supporting bracket, a weight hung thereon, a switch to which said weight is connected, a revolute governor including a shaft and a movable stem or rod, means for operating the governor, a pivotally-mounted trigger-lever connected to said stem or rod, said trigger-lever having an opening, and a pin carried by the pivoted arm and adapted to said opening.

In testimony that we claim the foregoing as our own we have hereto affixed our signatures in the presence of two witnesses.

JAMES A. MEHRHEN.
JOHN H. HOWARD.
